187,401

DECANTER

Alexander J. Whittle, Elmhurst, N.Y.

Application December 29, 1958, Serial No. 53,936

Term of patent 14 years

(Cl. D58—9)

Fig. 1.

Fig. 2.

Fig. 3.

Fig. 4.

Fig. 5.

Fig. 1 is a perspective view of a decanter, showing my new design;

Fig. 2 is a top plan view;

Fig. 3 is a rear elevational view;

Fig. 4 is an end elevational view; and

Fig. 5 is a bottom plan view of the same.

I claim:

The ornamental design for a decanter, substantially as shown.
